CENTER PUNCH

Thomas E. Darnell, Detroit, Mich.

Application October 23, 1947, Serial No. 781,589

4 Claims. (Cl. 33—191)

1

My invention relates to a new and useful improvement in a center punch and is intended primarily to provide a device for accurately centering the center punch relatively to the hole in a templet, pattern, die plate or the like so as to center punch the work-piece accurately relatively to the hole in such pattern or templet.

It is an object of the present invention to provide a center punch so arranged and constructed that it may be readily centered to holes of various sizes.

Another object of the invention is the provision in a center punch of a spring pressed punch so arranged and constructed that it may be released for movement to punching position in response to spring pressure.

Another object of the invention is the provision in a device of this class of means whereby the center punch may be moved to position for loading or compressing the spring and retaining the same in such position until released.

Another object of the invention is the provision in a center punch of a housing having a plurality of contact members swingably mounted thereon and swingable outwardly into engagement with a hole in which positioned in order to center the center punch relatively to said hole.

Other objects will appear hereinafter.

It is recognized that various modifications and changes may be made in the detail of structure illustrated without departing from the invention and it is intended that the present disclosure represents one embodiment of the invention.

Forming a part of this specification are drawings in which,

Fig. 1 is a side elevational view of the invention,

Fig. 2 is a central, longitudinal, sectional view of the invention with parts broken away and parts shown in section and other parts shown in side elevation, all slightly enlarged over that shown in Fig. 1.

Fig. 3 is a sectional view taken on line 3—3 of Fig. 2,

Fig. 4 is a sectional view taken on line 4—4 of Fig. 2;

Fig. 5 is a sectional view taken on line 5—5 of Fig. 2,

Fig. 6 is a sectional view taken on line 6—6 of Fig. 2,

Fig. 7 is a fragmentary, sectional view taken on line 7—7 of Fig. 2.

In the invention, I provide a housing comprising in part, a barrel 11 provided with the constricted opening 13 formed therethrough which is internally threaded and which opens at one end

2

into the recess 12. Threaded into this threaded opening 13 is an externally threaded sleeve 14 having a peripheral flange 15 formed in one end thereof. Slidably projected through this sleeve or member 14 is a punch 16 projecting outwardly from which is a pin 17 adapted to engage in the longitudinal slot 18 formed in the member 14. The chamber 19 of the barrel 11 terminates in a shoulder 20 on which engages a washer 21 bearing against which is one end of a coil spring 22 which embraces the punch 16. The opposite end of the spring 22 embraces, in snug engagement, the conical portion of a sleeve or tube 23, projecting upwardly from which, diametrically oppositely of each other, are the arms 24 and 25, each of which is provided with an engaging prong 26 adapted to engage behind the head 27 carried on the upper end of the punch or rod 16. The lower end of this punch is tapered, as at 14, to provide a center point.

The housing also comprises an extension tube 29 having a portion 30 reduced in outside diameter and telescoping inwardly of the section 11. The tube 23 projects through the end of this section 29. Formed in the end of the section 29 is a peripheral groove 31 in which engages a set screw 32 secured to the section 11 and projecting at one end into the groove 31 so that the section 29 is rotatable relatively to the section 11 while they are in fixed, axial relation. Also carried by the lower end 30 of the section 29 is an inwardly projecting screw 33 which engages in the longitudinally directed slot 34 formed in the member 25.

Slidably engaging in the member 29 is a tube 75 which is slotted intermediate its ends, the slots extending inwardly from one end as designated by the numerals 35 and 36 so that the end of the tube or member 75 is thus divided into a pair of substantially semi-circular segments in which are formed longitudinally directed slots 37 and 38 to provide the oppositely disposed gripping fingers 39 and 40. Projecting inwardly from the end of each of the members 39 and 40 is a gripping lug 41 adapted to project inwardly beyond the edge of the head 27 so that when the tube 75 is pulled outwardly of the section 29, these members 41 will engage behind the head 27 and move the center punch or rod 16 axially against the compression of the spring 51 and the spring 22, the washer 21 moving with the punch or rod 16. The members 24 and 25 are resilient so that as the head passes between the projections 26, these members 24 and 25 will spring outwardly and allow the members 26 to snap inwardly behind the head 27 thus holding the rod or center punch 16

in its position with the springs 51 and 22 under compression. Threaded into a threaded bore formed through the member 75 is a screw 42 having a tapered end 44 adapted to engage the inclined faces 45 of the ends of the members 24 and 25. By pressing inwardly of this screw 42, the members 24 and 25 will be swung apart to release the rod or center punch 16 for movement in response to the compression of the springs 51 and 22.

Projecting outwardly from the end of the section 11 are knuckles 46 extended through each of which is a pivot pin 47 to pivotally mount the contact leg 48 thereon. As shown in Fig. 3, I prefer to use three of these contact legs, although the number may be increased if desired. Projecting inwardly from adjacent the upper end of each of these legs is a flange or tongue 49 which engages the under surface of a washer 76 through which is slidably projected the center punch or rod 16. The nose 50 projects inwardly from the upper end of each of the contact legs and engages the outer face of the flange 49. One end of the spring 51, which embraces the rod or stem 16, bears against one face of the washer 76, and the other end bears against the washer 52 which is secured on the rod or center punch 16 by means of the pin 53.

The construction is such that when the parts are assembled, as described, the contact legs may be inserted at their ends in an opening 77 formed in the templet, die plate, pattern or the like, indicated by the numeral 78 and which is positioned over the work-piece 79 in which it is desired to form a duplicate of the hole 77. The holes 77 formed in the templet or die plate 78 are not all of the same size, but when the legs are inserted into the openings, the section 28 may be rotated relatively to the section 11 and through the engagement of the set screw 33 and the slot 34, the tube or sleeve 23 will be rotated. As shown in Fig. 5, the rod or punch 16 is provided with flat faces 28 at that portion which projects through the member 23 which is also provided with flat faces so that the rod or punch 16 is also rotated as the tube 23 rotates, and the member 14 will rotate to move inwardly or outwardly of the section 11 because of the engagement of pin 17 in slot 18. As it moves inwardly the legs 48 will draw toward each other and as the member 14 moves outwardly, the legs 48 will be pressed outwardly to spread apart. In this manner, the legs may be brought into engagement simultaneously with the inner surface of the opening 77 regardless of the size so long as it is a size within the limits of the mechanism. When this engagement is effected and a tight contact is made with the side wall of the opening, the center punch 16 will be accurately centered relatively to the opening 77. Thereupon, upon pressing down on the screw 42, the members 24 and 25 may be sprung apart permitting the center punch 16 to move downwardly in response to compression of the springs 22 and 51 to engage the work-piece 79 and center mark the same. The projection of the center punch 16 beyond the end of the housing is such as to extend slightly beyond the ends of the contact legs 48 when they are in their most contracted position. After the center marking has been effected, it is but necessary to again pull the center punch 16 upwardly to cause the members 26 to engage beneath the head 27 and the device is again ready for operation. Should it be desired to center punch round stock, the periphery of

such stock may be engaged in the cut-away portions 55 of the ends of the legs.

In this way, I provided a simple and effective device whereby the center punching may be accurately accomplished and the operation easily and quickly performed where it is desired to center punch for a plurality of openings of various sizes. In this way, the use of several tools of different sizes is eliminated and a considerable saving in labor is accomplished, as well as a more accurate and efficient center punching performed.

What I claim as new is:

1. In a center punch of the class described, a housing comprising an upper and a lower tubular section, the upper section telescoping at its lower end with the upper end of said lower section, said sections being relatively rotatable and fixed axially; a center punch slidably projecting at one end into said housing and at its opposite end outwardly beyond the lower end of said lower section, the inner end of said punch being located in said upper section; a sleeve projecting through the lower end of said upper section and extending into said lower section, said sleeve being non-rotatable relatively to said upper section and embracing the inner end of said punch, said punch slidably projecting therethrough and being non-rotatable relatively thereto; a head on the inner end of said punch; a pair of diametrically opposite spring arms projecting from the upper end of said sleeve and extending toward the upper end of said upper section; and an engaging prong on each of said arms projecting inwardly therefrom adjacent the free end thereof for engaging behind said head and securing said punch against axial movement.

2. In a center punch of the class described, a housing comprising an upper and a lower tubular section, the upper section telescoping at its lower end with the upper end of said lower section, said sections being relatively rotatable and fixed axially; a center punch slidably projecting at one end into said housing and at its opposite end outwardly beyond the lower end of said lower section, the inner end of said punch being located in said upper section; a sleeve projecting through the lower end of said upper section and extending into said lower section, said sleeve being non-rotatable relatively to said upper section and embracing the inner end of said punch, said punch slidably projecting therethrough and being non-rotatable relatively thereto; a head on the inner end of said punch; a pair of diametrically opposite spring arms projecting from the upper end of said sleeve and extending toward the upper end of said upper section; and an engaging prong on each of said arms projecting inwardly therefrom adjacent the free end thereof for engaging behind said head and securing said punch against axial movement; and a threaded member carried by the upper end of said upper section and threadable inwardly and outwardly thereof and adapted upon inward threading for engaging the ends of said arms and springing the same apart for disengaging said prongs from said head.

3. In a center punch of the class described, a housing comprising an upper and a lower tubular section, the upper section telescoping at its lower end with the upper end of said lower section, said sections being relatively rotatable and fixed axially; a center punch slidably projecting at one end into said housing and at its opposite end outwardly beyond the lower end of said lower section, the inner end of said punch being located in said upper section; a sleeve projecting through

the lower end of said upper section and extending into said lower section, said sleeve being non-rotatable relatively to said upper section and embracing the inner end of said punch, said punch slidably projecting therethrough and being non-rotatable relatively thereto; a head on the inner end of said punch; a pair of diametrically opposite spring arms projecting from the upper end of said sleeve and extending toward the upper end of said upper section; and an engaging prong on each of said arms projecting inwardly therefrom adjacent the free end thereof for engaging behind said head and securing said punch against axial movement; and a threaded member carried by the upper end of said upper section and threadable inwardly and outwardly thereof and adapted upon inward threading for engaging the ends of said arms and springing the same apart for disengaging said prongs from said head; and a spring member cooperating with said punch for forcing said punch outwardly of said housing at the lower end thereof upon disengagement of said prongs with said head.

4. In a center punch of the class described, a housing comprising an upper section and a lower section, said sections being axially fixed and relatively rotatable; a sleeve mounted in said housing and rotatable in unison with said upper section; a punch slidably projected at one end into said housing and projecting through said sleeve and being axially moveable relatively to said sleeve and non-rotatable relatively thereto; an externally threaded sleeve threaded into the lower end of said lower section, said punch slidably projecting through said sleeve and rotatable in

unison with said externally threaded sleeve for transmitting rotative movement to said externally threaded sleeve upon relative rotation of said housing sections; a plurality of legs swingably mounted at one of their ends on the lower end of said lower section and engageable at their free ends in an opening in a work piece for engaging the sides thereof and centering the punch relatively to said opening; a nose on each of said legs at the end mounted on said housing engageable with the end of said externally threaded sleeve upon outward threading of the same for spreading said legs apart.
